UNITED STATES PATENT OFFICE.

JOHN P. MENTZER, OF CHICAGO, ILLINOIS.

LOOSE-LEAF BINDER.

1,137,012.

Specification of Letters Patent. Patented Apr. 27, 1915.

Application filed October 27, 1913. Serial No. 797,376.

To all whom it may concern:

Be it known that I, JOHN P. MENTZER, a citizen of the United States, residing at Chicago, in the county of Cook and State of Illinois, have invented a certain new and useful Improvement in Loose-Leaf Binders, of which the following is a full, clear, concise, and exact description, reference being had to the accompanying drawings, forming a part of this specification.

My invention relates to loose leaf binders.

Prominent objects of the invention are to provide a simple, practical and effective device of the class specified; to simplify the construction and reduce the expense of manufacture, and to secure quickness and accuracy, and effectiveness of operation, and to secure other desired results, as herein-after pointed out.

In the accompanying drawings, Figure 1 is an end elevation of a loose leaf binder embodying my invention; Fig. 2 is a view of a portion of the binder with the covers opened so as to show the leaf holding device in different positions; Figs. 3 and 4 are sections taken on lines 3—3 and 4—4 respectively in Fig. 2.

In the drawings I show a loose leaf binder having covers 1—1, and a back 2, and I show the same provided with a series of loose leaves 3. To the back 2 is attached the leaf holding structure which more especially embodies my present invention. This preferably comprises a pair of bars or rods 4, 5 which are secured or mounted upon the back 2 for pivotal or swinging motion, as by a screw 6. Each of the bars 4, 5, is provided at its end with upright curved members 7 and 8 respectively. These members are preferably substantially semi-circular in form, so that the two together form a substantial circle, which is parallel to the circle formed upon the opposite ends of said bars. These curved members 7 and 8 are adapted to fit together and to separate by the pivotal or scissor-like movement of the bars 4 and 5, which are crossed to produce a separation of the ends of the bars 4 and 5. One of the bars as 5 is downwardly offset as shown at 5^a to permit the corresponding ends of both bars 4 and 5 to travel in the same relative plane, thus permitting the same circular parts 7 and 8 of the rings to be interchangeably mounted upon either end of the bars, eliminating the necessity of any alterations thereto, which would follow if the ends of

the bars traveled in different planes. This enables the loose leaves to be put into position in the binder and also taken out of the same by separating the bars 4 and 5 so as to open the two rings formed at the opposite ends of said bars by said semi-circular members. When the leaves are in place or removed the members are closed together so as to hold the remaining leaves in proper position. The members 7 and 8 are preferably made of separate pieces of metal and secured to the ends of the bars 4 and 5 in any desirable way, as for example by rivets 9—9.

The bars 4, 5, are snapped closed by lugs 10, 10, fitting into recesses 11, 11. Too wide opening or separation of the bars is prevented by lugs 12, working in slots or recesses 13.

It will be seen that the arrangement is simply and easily operated involving but very few parts, and can be manufactured at very low expense.

It will be understood that changes and modifications can be made without departing from the spirit of the invention.

What I claim is:

1. A device of the class described comprising in combination, a pair of bars both pivoted between their ends at a common pivot, the opposite ends of each bar being separated from the corresponding end of the other bar when in closed position, one part of an openable leaf holding member mounted upon each end of each bar and forming a pair of substantial rings when closed and the holding rings formed upon the opposite ends of both bars being parallel to each other when in closed position.

2. A device of the class described comprising in combination, a pair of bars both pivoted between their ends at a common pivot, the opposite ends of the bars being bent so as to diverge from one another at their ends when in closed position, one part of an openable leaf holding member mounted upon each end of each bar and forming a pair of substantial rings when closed, the holding rings formed upon the ends of the bars being parallel to each other when closed, and means for limiting the movement of the bars in one direction.

3. A device of the class described comprising in combination, a pair of bars pivoted between their ends at a common pivot, the opposite ends of each bar being nor-

mally separated from the corresponding ends of the other bar when in closed position, the corresponding ends of both bars being movable in the same plane, and co-
6 acting leaf holding members mounted upon the ends of the bars.

4. A device of the class described comprising in combination, a pair of bars pivoted between their ends at a common pivot,
10 each end of each bar being provided with one part of an openable leaf holding means, and the corresponding ends of both bars being movable in the same plane when the openable leaf holding members are operated
15 to open or close said means.

5. A device of the class specified comprising in combination, a pair of bars pivoted together between their ends, one of said bars being flat and the other being bent
20 downwardly at its ends so that the bent down portions lie in the same plane as the ends of said flat bar, the ends of both bars being bent so as to diverge from one another when in a closed position, and leaf
25 holding members formed of pieces which are separate from the bars and secured to the ends of the same, said members having

their lower ends provided with lateral extensions which are secured to the bent end portions of the bars.

6. A device of the class described in combination, a pair of coöperating pivoted bars of uniform width throughout their length, the free ends of both bars being provided with one part of a filing device, the ends of one of said bars being laterally offset, and movable in the same plane with the ends of the bar which carries the other filing member.

7. A device of the class described in combination, a pair of coöperating pivoted bars of uniform width throughout their length, the free ends of both bars being provided with one part of a filing device, both ends of said bars which carry the filing devices being laterally offset and movable in substantially the same plane.

In witness whereof, I hereunto subscribe my name this 25th day of October, A. D., 1913.

JOHN P. MENTZER.
